UNITED STATES PATENT OFFICE

WILLIAM A. COTES, OF LANSING, MICHIGAN, ASSIGNOR TO REO MOTOR CAR COMPANY,
OF LANSING, MICHIGAN, A CORPORATION OF MICHIGAN

SEAM ROLLING MACHINE

Application filed August 8, 1927. Serial No. 211,567.

This invention relates to seam rolling machines and more especially to a novel construction tending to simplify, render more efficient and improve generally devices of this character.

The invention has among its objects to provide a machine of this character in which the seam bending or pressure roller is provided with means for guiding the same whereby the bending roller may be caused to follow the seam on a tank, container or the like, which is irregular in cross section as, for instance, a tank rectangular in cross section. The invention also contemplates the provision of means for automatically successively increasing the pressure exerted by the bending roller upon the seam so that the seam is gradually bent tighter until finished, together with means for automatically releasing the pressure roller at the completion of each operation. The apparatus herein described also contemplates means for automatically stopping the machine at the end of each operation and of a safety device preventing starting of the machine until the work is properly placed.

The several objects, advantages and novel details of construction of this invention will be made more apparent as this description proceeds, especially when considered in connection with the accompanying drawings wherein:

Figure 1 is a perspective view of a machine as viewed from the front thereof.

Figure 2 is a perspective view of a machine as viewed from the rear thereof.

Figure 3 is an enlarged vertical sectional view partly in elevation showing the seam rolling machine and its associated mechanism.

Figure 4 is a similar view with the bending member in released position.

Figure 5 is a detail elevational view.

Figure 6 is a semi-diagrammatic view showing a tank with the heads in position to have the seams thereof rolled, and

Figure 7 is a semi-diagrammatic view of one end of the tank after the seam has been rolled.

Referring now particularly to the draw-

ings wherein like reference characters indicate like parts and more especially to Figures 6 and 7 thereof, it will be noted that the problem involved is that of connecting the heads H to a tank T. Each head H is provided with a peripherally return-bent portion forming a flange F which is open to receive the adjacent end of the tank body T and the machine forming the subject matter of this invention is adapted to roll the flange F downwardly so as to form a tight seam with the flange F bent against the body T as clearly shown in Figure 6. During rolling the seam is formed with an offset O which serves to clinch or lock the same as will be clearly apparent from Figure 7.

Referring now more particularly to Figures 1 to 5 inclusive, it will be noted that the machine includes a table-like base or support 10 which may be conveniently mounted upon legs 11. Rotatably journaled in supports 12 rising from the base 10 are heads 13 which are adapted to receive and support the tank heads H during the seam rolling operation. Each head 13 is carried by a shaft 14 and is adapted to be rotated through gearing not shown in detail. It is sufficient only to state that gearing is provided for rotating the pair of heads 13 synchronously. In order to facilitate the placing of the work one of the heads 13 is adjustable and by reference to Figure 5 it will be noted that while the shaft 14 which carries this head is rotatable by means of gearing such, for instance, as the gears 15 and 16, nevertheless a sleeve 17 is associated with the shaft 14 which sleeve is provided with teeth 18 which mesh with a pinion 19 fixed to a shaft 20, which shaft is rotatable by means of a handle 21. The width of the gears 15 and 16 is such that even when slid relative to one another these gears will still remain in mesh. In Figure 5 the head 13 is shown retracted but when the handle 21 is rotated toward the right or in a clockwise direction sleeve 17 will be slid through bearing support 12 and as a consequence will slide shaft 14 together with head 13 and gear 15 which will project head 13 toward its companion head. Inasmuch as the work is placed in position by first locating heads H upon the

respective heads 13 and then positioning the body T therebetween a movement of one of the heads 13 toward the other will bring the tank heads H into such a position that the ends of the tank body will enter the recesses formed by the return bent flanges F whereupon the tank body is supported and the seams are ready for rolling.

Associated with each head 13 is a seam rolling, or work engaging member which consists of an arm 22 carrying a seam engaging roller 23 at one end thereof. The other end of lever 22 is preferably sleeved as at 24 and rockably journaled by means of this sleeve 13 upon a shaft 25. This shaft extends longitudinally of the machine and is mounted in bearing supports 26. Associated with each seam rolling member is a control or guiding member consisting of an arm 27 provided 15 with a roller 28 at one end thereof, the other end being sleeved as at 29 and also rockably journaled on shaft 25. Lever 27 is provided with a short arm 30 which extends to the other side of shaft 25 and journaled in the 20 end of this short arm 30 is a shaft 31. Fixed to rotate with shaft 31 is a ratchet wheel 32 and a cam 33 provided with a cam surface 34 and a recess 35. A dog 36 is pivotally mounted as at 37 to a fixed part of the machine as, 25 for instance, the support 26 and this dog is normally urged into engagement with ratchet wheel 32 by means of a spring 38. Pivotally connected to lever 22 as at 39 is a coupling member in the form of a bell crank segment 30 40. A roller 41 journaled on the coupling member 40 is adapted to engage cam 33, the coupling member being also provided with an adjustable stop 42 engageable with the lever 22, this stop being here shown as in the form 45 of a set screw which may be adjusted and secured in its adjusted position by means of a lock nut 43.

Associated with each head 13 is a master cam 44 with which roller 28 of arm 27 is 45 adapted to engage. Thus upon rotation of each head the cam 44 associated therewith rocks or oscillates arm 27 and by reason of the mechanism just previously described and in a manner to be more fully hereinafter set forth, bending member 22 is rocked to maintain the pressure roller 23 in engagement with the seam.

Pivotally mounted to the base 10 of the machine, as at 45 is a bell crank 46, an end 47 50 of which constitutes a step up dog for advancing the ratchet wheel 32 for a purpose to appear more fully hereinafter. The other end 48 of this bell crank lever is connected by means of a rod 49 to a bell crank lever 50 pivotally connected as at 51 to the base 10 of the machine. The other end 52 of this bell crank lever constitutes a handle by means of which the step up dog 47 may be operated.

By comparison of Figures 3 and 4 the operation 55 of the mechanism thus far described will

be more apparent. The seam bending member 22 and the guiding member 27 are capable of independent oscillation upon shaft 25. However, they are coupled together for synchronous oscillation by means of the bell crank segment 40 which bears through the adjustable stop 42 against lever 22 and by means of roller 41 which engages cam 33. Thus with roller 23 engaging the seam to be 60 rolled and roller 28 bearing against master cam 44 this latter cam, when rotated will rock lever 27 and will consequently rock lever 22 and cause the same to follow the rectangular cross section of the tank. As will be apparent from Figure 4 when roller 41 reposes in recess 35 of cam 33 levers 22 and 27 will be 65 permitted to move apart to assume their inoperative position and at this time the rotation of the work piece is stopped and the completed work piece removed and another inserted. In starting the machine the ratchet wheel 32 is stepped up by operating step up dog 47 through handle 52 to thus rotate cam 33 sufficiently to bring roller 41 out of recess 70 35 and into engagement with the beginning of cam surface 34. The rotation of the heads 13 is started and as the levers 22-27 oscillate about shaft 25 ratchet wheel 32 is in consequence rocked in an arcuate path about shaft 25. In consequence of the engagement of dog 75 36 therewith, it being understood that this dog is mounted to a fixed part, a rotation of ratchet wheel 32 results in the direction of arrow A, see Figure 3. This movement of ratchet wheel causes a similar movement of cam 33, 80 which through roller 41, bell crank segment 40 and stop pin 42 exerts a pressure against lever 22 causing the same to move toward lever 27 and thus exert a successively increasing pressure upon the seam being rolled. This action 85 continues until one complete revolution of cam 33 whereupon roller 41 again drops into recess 35 thereby again permitting arms 22 and 27 to move away from one another. At 90 such time the seam has been rolled tightly as 95 shown in Figure 7 of the drawings.

In order to automatically stop the rotation of the heads 13 at the completion of each seam rolling operation the following construction is provided. When the levers 22 and 27 move apart lever 27 drops away from cam 44 by gravity and engages a pin 53 which extends upwardly through the base 10 to a point immediately under lever 27. This pin is pivotally connected as at 54 to an arm 55 fixed to a shaft 56 journaled in the bed of the machine. Also fixed to shaft 56 is an arm 57 to which is connected a rod 58. This rod extends longitudinally of the machine and operates a clutch (not shown) contained in clutch housing 59. This clutch may be conveniently employed for connecting or disconnecting a constantly driven shaft driven by pulley wheel 60 to drive shaft 61 which 100 extends longitudinally of the machine and is 105 110 115 120 125 130

connected by suitable gears (not shown) to the shafts 14 upon which the heads 13 are mounted. However, when lever 27 depresses pin 53, rod 58 is actuated to disengage the clutch thus stopping rotation of heads 13.

5 In order to prevent the starting of the machine until such time as the adjustable head 13 has been projected toward the other head a construction is provided as follows:

10 Fixed to shaft 56 is an arm 62 which is connected by a link 63 to an arm 64 fixed upon shaft 65. This shaft is rotatable by means of a handle 66 and upon rotation will actuate rod 58 to cause engagement of the clutch 15 to start the machine. However, also mounted upon shaft 65 is a safety dog 67 which is adapted to enter a recess 68 formed in a ratchet wheel 69 fixed to rotate with shaft 20 when handle 21 is oscillated to bring head 25 13 into operative position. However as seen in Figure 5, when head 13 is retracted or out of operative position recess 68 is out of registration with dog 67 so that should an attempt be made to operate handle 66 to start the machine it will be impossible to complete the clutch engaging operation as the dog 67 will contact with the periphery of the ratchet wheel 69 to prevent further movement of lever 66. However, after handle 21 has been 30 operated to move head 13 to operative position recess 68 will be opposite dog 67 and handle 66 will then be operated to cause an engagement of the clutch to start the machine.

It will be obvious that the master cam 44 35 will be designed with reference to the contour of the tank or container or the like which is to be seamed. Thus while the master cams herein illustrated are shown as of a particular design or configuration this design of cam 40 is peculiar to the cross sectional shape of the tank or work piece herein illustrated. It will likewise be understood that any type or design of driving mechanism may be provided and for this reason the particular construction and arrangement of gears has only 45 been briefly referred to as this forms no essential part of this present invention. Likewise many of the essential and all of the non- 50 essential details of the invention may be altered without departing from the spirit and scope of this invention and to this end reservation is made to make such changes as may come within the purview of the accompanying claims.

55 What I claim as my invention is:

1. In a machine of the class described, means for rotating a work piece, a seam rolling member, a pressure control means therefor, means for moving the seam rolling member in conformity with the contour of the seam, and means actuated by the said movement of said seam rolling member for actuating said pressure control means.

60 2. In a machine of the class described, a seam rolling member, a control means there-

for and means for successively increasing the pressure of said seam rolling member on said seam including a cam and an automatically operated ratchet for actuating said cam.

70 3. In a machine of the class described, a seam engaging member, a control member therefor and means connecting said control member to said seam engaging member including an automatically operated cam carried by one of said members and means carried by the other member and engageable by said cam for increasing the pressure exerted by the seam engaging member.

75 4. In a seam rolling machine, a seam engaging member, means for oscillating said member to cause the same to follow the seam of a rotating tank rectangular in cross section, and means actuated by the said oscillation of said seam engaging member for successively increasing the pressure of said member upon said seam.

80 5. In a machine of the class described, a seam engaging member, a control member therefor, ratchet controlled cam means for moving said seam engaging member to cause the seam to gradually increase the pressure exerted thereby upon the work and means for rendering said member inoperative.

85 6. In a machine of the class described, a seam rolling member, a control member therefor, automatic means for moving said seam rolling member in a direction in which it exerts a successively increasing pressure upon said seam and means operable after a predetermined time for rendering said member inoperative.

90 7. In a device of the class described, means for rotating a work piece, a seaming member engaging the work piece, a control member therefor, means for oscillatably mounting said members, a cam engaging said control member for oscillating said members and means for holding said members in engagement with said work piece and cam respectively.

105 8. In a device of the class described, means for rotating a work piece, a seaming member engaging the work piece, a control member therefor, means for oscillatably mounting said members, a cam engaging said control member for oscillating said members and automatic means for holding said members in engagement with said work piece and cam respectively for a predetermined period.

110 9. In a device of the class described, means for rotating a work piece, a seam rolling member engaging the work piece, a control member therefor, means for oscillatably mounting said members, a cam engaging said control member for oscillating said members and means for holding said members in operative position including means for relatively moving said members to cause said seam roll-

ing member to exert a successively increasing pressure upon the work piece.

10. In a device of the class described, means for rotating a work piece, a rotatable cam, a seam engaging member, a control member therefor engageable with said cam, means for oscillatably mounting said members and means for preventing independent oscillation of said members for a predetermined period.

15. In a device of the class described, means for rotating a work piece, a rotatable cam, a seam engaging member, a control member therefor engageable with said cam, means for oscillatably mounting said members and means for causing said members to oscillate as a unit including means for causing said seam engaging member to exert a successively increasing pressure upon said seam.

20. In a machine of the class described, an oscillatable seam rolling member, an oscillatable control member therefor, a shaft upon which said members are mounted, a cam carried by one of said members, dog and ratchet means for automatically operating said cam, a bell crank lever pivotally mounted upon the other member, one end of said lever engaging said member and the other end of said lever being influenced by said cam for changing the relative positions of said members.

25. In a machine of the class described in which the work is rotated, a rotary cam, a seam rolling member, a shaft upon which said member is oscillatably mounted, a control lever having one end engaging said cam and oscillatably mounted intermediate its ends upon said shaft, a cam carried by the other end of said lever, means for actuating said cam upon an oscillation of said lever and means carried by said seam rolling member engaging said cam whereby said seam rolling member is moved with successively increasing pressure against said work.

30. In a device of the class described, the combination with seam rolling mechanism and means for rendering said mechanism inoperative at predetermined intervals, of a driving mechanism and means operated by said seam rolling mechanism when inoperative for disconnecting said driving mechanism.

35. In a device of the class described the combination with seam rolling mechanism including a control member and means operable at predetermined intervals for rendering said means inoperative wherein said control member drops by gravity, of a driving mechanism for said device including a clutch and means operated by said control member for disengaging said clutch.

40. In a device of the class described, a movable work engaging head, means for shifting said head, a starting lever and means

45. preventing actuation of said starting lever until said head is shifted into operative position.

50. 17. In a device of the class described, a movable work engaging head, means including a shaft for moving said head, a starting lever and a dog operated by said lever and engaging said shaft to prevent actuation of said starting lever until said head is in operative position.

55. In testimony whereof I affix my signature.

WILLIAM A. COTES.
